ANCHORING MEANS FOR SANITARY DRINKING CAPS

Paul Nelson Fleming, Hagerstown, Md.

Application March 14, 1941, Serial No. 383,445

1 Claim. (Cl. 215—100)

This invention relates to a sanitary drinking cap for bottles and the like, and has for one of its objects the production of a simple and efficient cap which may be easily attached to the mouth of a bottle to facilitate drinking from a bottle, and at the same time shield the lips of the user so that the end of the bottle neck will be prevented from contacting with the lips of the user.

A further object of this invention is the production of a simple and efficient sanitary drinking cap having an inserting neck for fitting within the neck of a bottle and an overhanging or encasing flange for encasing the outer bead of the neck of a bottle to provide a sanitary shield for the bottle neck while drinking, the inner neck and outer bead providing a brace for firmly holding the drinking cap upon a bottle.

Other objects and advantages of the present invention will appear throughout the following specification and claim.

In the drawing:

Figure 1 is a perspective view of the cap;
Figure 2 is a vertical sectional view of the cap;
Figure 3 is a horizontal sectional view taken on line 3—3 of Figure 2;

Figure 4 is a horizontal sectional view taken on line 4—4 of Figure 2; and

Figure 5 is a vertical sectional view of a modified form of the invention.

By referring to the drawing, it will be seen that 10 designates a bottle neck which is provided with a conventional cap-retaining bead 11. In carrying out my invention, the conventional crimped cap is removed and my improved sanitary drinking cap 12 is attached to the outer end of the neck of the bottle. This cap 12 is preferably formed of resilient waxed card-board, or other material, which may be obtained at a minimum cost. Light metal or other similar material, may be used without departing from the spirit of the invention. The sanitary drinking cap may be easily stamped or pressed from sheet material and manufactured by automatic machinery.

The sanitary drinking cap 12 is provided with a drinking spout 13 which is open at its outer end 14 and along one side thereof, as at 15, for the full length of the spout 13 to the point where the spout 13 joins the wall 16, as shown. The spout 13 extends outwardly of the outer wall 16 and is inset from the outer periphery of the wall 16. The side edges of the cut-away portion 15 are gradually curved from a point approximately the longitudinal center of the spout 13 outwardly in the direction of the edge of the cap and merge into the outer wall 16. All edges are smooth to

avoid injury to the mouth of the user. The wall 16 is provided with an aperture 17 formed within the inner end of the spout 13, and extends laterally of the cut-out portion 15, as shown.

5 A depending or inwardly extending neck 18 is carried by the inner face of the wall 16, which neck 18 is adapted to extend into the neck 10 of the bottle. The inner edge of the neck 18 is preferably inturned, as at 19, to reinforce the inner edge of the neck 18, and also to facilitate the insertion of the neck 18 into a bottle. An inturned annular rim 20 is formed at the outer periphery of the wall 16 and overhangs the neck 18. The edge of the rim 20 is slightly out-turned, as at 21, to facilitate the forcing of the rim 20 over the bead 11 of the bottle and also reinforce the rim 20. The neck 18 is preferably tapered toward the in-turned portion 19 to facilitate the insertion of this neck 18 in the bottle, and this neck 18 is preferably longer than the overhanging inturned rim 20, so that the neck 18 will extend well into the bottle and the rim 20 will overlie and encase the bead 11.

When the sanitary drinking cap 12 is attached 25 to a bottle, the neck 18 fits snugly in the mouth of the bottle, and the rim 20 fits snugly over the bead 11 in a manner whereby the neck 18 and rim 20 will brace and reinforce each other and hold the cap 12 against accidental displacement when in use.

30 Since the rim 20 overlies the side of the bead 11, and the wall 16 fits over the outer end of the bead 11, the outer end of the bottle will be encased thereby shielding the lips of the user and preventing his lips from coming in direct contact with the bottle.

35 This device provides a sanitary shield as well as a means whereby a user may conveniently drink the contents direct from a bottle without the necessity of using an unhandy and unsatisfactory drinking straw. The device may be readily

40 applied to the conventional soft-drink or similar bottle and through the use of this cap, the flow of liquid may be easily controlled by the user and the danger of spilling the contents upon the clothing is reduced to a minimum. The user may control the flow by regulating the size of the vent through the cut-away portion 15 by increasing or decreasing the size of the vent when moving his upper lip over the vent.

45 In Figure 5, there is shown a modified form of the cap having a drinking spout 22, an elongated outer rim 23, and an inner neck 24. This constitutes a modified design which may be advisable for use with some bottles.

Having described the invention, what is claimed 50 as new is:

As an article of manufacture, a sanitary drinking cap having an outer flat wall, a flange carried by the outer edge of said wall and adapted to overhang the bead of the neck of a bottle, said wall having a central aperture inset from the outer edge of the cap to provide a wide flat lip-abutment portion entirely surrounding the aperture, an open-sided spout partly surrounding said aperture and protruding outwardly of the flat wall adjacent the edge of the aperture, the open-sided spout defining a vent opening longitudinally of one side of the spout over which the upper lip of

a user may extend, the flat-abutment portion adjacent the open side of the spout being also adapted to be engaged by the lip of a user in a valve-like manner to control the flow of liquid out through the spout and into the mouth of the user, an inset annular neck formed around said central aperture upon the opposite face of said flat wall relative to said spout and adapted to fit into the neck of a bottle for anchoring the cap upon the neck of a bottle and for directing the contents of a bottle through said spout.

PAUL NELSON FLEMING.
